(57) **CLAIM**

The ornamental design for a sensor housing, as shown and described.

DESCRIPTION

FIG. 1 is a perspective view of a sensor housing according to the design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the drawings illustrate environmental subject matter only and form no part of the claimed design.

1 Claim, 6 Drawing Sheets
